Alfred J. Morrison

UNITED STATES PATENT OFFICE.

ALFRED J. MORRISON, OF DENVER, COLORADO, ASSIGNOR TO STOKES & SMITH COMPANY, OF SUMMERDALE, PHILADELPHIA, PENNSYLVANIA, A CORPORATION OF PENNSYLVANIA.

EXTENSION-BOTTOM-BOX-WRAPPING APPARATUS.

1,348,369.

Specification of Letters Patent.

Patented Aug. 3, 1920.

Application filed September 26, 1919. Serial No. 326,508.

To all whom it may concern:

Be it known that I, ALFRED J. MORRISON, a citizen of the United States, and a resident of the city of Denver and State of Colorado, have invented certain new and useful Improvements in Extension-Bottom-Box-Wrapping Apparatus, of which the following is a specification.

This invention relates to machines for covering pasteboard boxes, and particularly to devices used in wrapping the extension bottom type of box.

In wrapping pasteboard boxes it is the general practice to attach a glued wrapper blank to the bottom of a set up box shell and then to force the shell, bottom first, between a series of operating elements which fold in and press the parts of the wrapper against the sides and ends of the box and over its top edges in proper succession, so as to cover the box completely and press the glued wrapper evenly into place thereon.

This operation presents difficulties where the box is of the extension bottom type, since the wrapper must be pressed against the top of the extension flange before it is brought into contact with the adjacent side of the box; and as it is highly desirable to have the box in continuous motion during the operation, the device for wrapping the top of the flange must move in the same direction as the box while performing its wrapping function.

One method of performing this operation is disclosed in the patent to C. A. Garrett, No. 872,925; and the object of the present invention is to improve upon the general type of mechanism disclosed therein. In said patent parallel rollers are longitudinally slotted to receive opposite extension bottom flanges of a box shell descending bottom first between the rollers with the glued wrapper blank attached to the bottom of the shell. The edges of the extension flanges in their descent contact with the lower faces of the slots and rotate the rollers inwardly toward the box, the slots being so proportioned that their upper edges wipe the opposite flaps of the wrapper inwardly over the extension flanges and into contact with the upper side thereof, the continued motion of the box rolling the unbroken surface portion of the rollers up-

wardly against the sides of the box to press the wrapper flaps into close contact therewith. A second set of parallel rollers located below the first set similarly operates on the two remaining sides of the box; but as their operation is exactly the same as that of the top pair of rollers, it will not be described.

Rollers of this type may obviously be used in any machine adapted to wrap box shells by the method above outlined, that is, by passing a shell with the glued wrapper attached to the bottom thereof through a series of operating elements; but for the purpose of illustration it is disclosed as attached to a box covering machine of the type disclosed in the patent to Philip S. Smith, No. 691,329.

In this type of machine the box shell, with its attached cover blank, is registered on a thin platen corresponding in size to the extension bottom, and a form block connected with a plunger rod is located inside the shell and moves downwardly against the yielding resistance of the platen, the relatively thin edges of the platen entering the slots in the wrapping rollers and protecting the extension flanges from being broken thereby.

The roller disclosed in the abovementioned patent to Garrett has a longitudinal slot formed with straight, flat sides. During the wrapping operation the upper wall of the slot which presses the wrapper into engagement with the upper face of the extension edge is practically pivoted about the outer edge of the extension as the roller revolves until it reaches the position shown in Figure 4 of said patent. At this moment, and not before, the wrapper is pressed against the extension edge over a substantial portion of its surface; but a moment later the further descent of the box lifts the upper wall of the slot away from said extension except at the edge of the slot wall, which slides inwardly into position against the wall of the box. It will be seen that the slot wall has practically a rocking motion about the edge of the extension and the edge of the slot as pivots, and is in substantial pressing engagement with the wrapper and extension edge for only a moment during the operation. Furthermore, in the position of the rollers shown in Fig. 4 of

said patent, the upper edge of each slot is necessarily above the center of the rollers. Consequently, the further descent of the box and rotation of the roller wipes said edge inwardly toward the box and along the upper face of the flange; and as the wrapper is bent up sharply around the edge there is a decided resistance to this sliding movement tending to prevent the edge of the roller from passing completely into the angle between the extension flange and the side wall of the box to make a clean, sharp bend in the wrapper at that point, the resilient buffer located in the roller slot permitting the edge of the slot to be withdrawn very slightly from the close contact which is necessary to press the wrapper into proper position. This defect is accentuated by the fact that the box descends with considerable speed in the type of machine disclosed in the Smith patent, increasing the tendency of the upper edge of the slot to jump across the angle between the extension flange and the box wall.

I have removed this difficulty by curving the upper wall of the slot outwardly adjacent its outer edge, the curve being so designed that when the roller reaches the point where the walls of the slot are approximately horizontal, as shown in Fig. 4 of the Garrett patent, the upper wall of the slot will contact with the upper side of the extension flange only adjacent its outer edge, and the continued descent of the box and consequent rotation of the rollers will roll the upper wall of each slot inwardly over the extension edge under the resilient pressure afforded by the buffer, the outer edge of the slot being so shaped that the tangents to the curved wall and the outer curve of the roller at their intersection are at approximately a right angle, or, stated in another way, a plane through the axis of the roller and the outer edge of the curved portion of the wall will be tangent to the curved portion at its edge. Consequently, this edge is adapted to press the wrapper firmly and smoothly into the junction between the extension flange and the side wall and to produce a sharp, clean cut right angled bend in the wrapper.

Other objects and advantages of my invention will be apparent from the following description taken in connection with the accompanying drawings, in which:—

Fig. 1 is an end view of my invention applied to a box covering machine of the type disclosed in the Smith patent, showing part of the support for the rollers, the box, adjacent supporting parts of the machine and part of the rollers being shown in section, and

Figs. 2, 3, 4 and 5 are fragmentary cross-sectional views of one roller and adjacent portions of the box shell, wrapper and supporting parts, showing the successive steps

in the operation of applying the wrapper to the extension flange.

The box shell 10 is glued to an extension bottom 11 having a flange 12 projecting beyond the side walls of the box 10. A wrapper 13 cut to the proper shape is coated on one side with adhesive and the extension bottom 11 is placed thereon in proper position. Any suitable mechanism may be provided for engaging the box shell, with the wrapper attached, and passing it between the rollers. In the form of machine above referred to, the box is registered on a platen 14 mounted to reciprocate between the rollers. A form block 15 carried by the end of reciprocating plunger 16 is located inside the box shell; and the combined action of the form block and platen maintains the box in position during the wrapping operation. A pair of oppositely located parallel wrapping rollers 17 extend into the path of the extension flanges 12 and the adjacent edges of platen 14, which is dimensioned so as to register accurately with the edges of the extension bottom 11. Rollers 17 are mounted in any suitable way, such as by yokes 18 carrying the usual bearings for the gudgeons of the rollers, and preferably mounted on the frame of the wrapping machine. Each roller is provided with a diametrically located longitudinal slot 19 of substantial width. In this slot is resiliently mounted a buffer element, preferably consisting of a longitudinal rod 20 slidable transversely in the slot. Any desired method of mounting may be provided, such as the screw studs of the Garrett patent, springs 21 being inserted between the rod and the bottom of the slot to force it normally outward. The outer face of the rod 20 is beveled at 22 to form what may be referred to as a cam surface, tending to press the upper wall 23 of the slot resiliently against the upper surface of the extension flange when the downward motion of the box introduces the flange into the slot in the manner above described.

The method of operation of the roller will be apparent from Figs. 2 to 5. The descending extension flange first enters the slot, as shown in Fig. 2, the roller being provided with any resilient mounting, such as that disclosed in the Garrett patent, tending to maintain it in its upward position shown in said figure. A slight descent of the box rotates the roller until the upper slot wall 23 contacts with the edge of the flange 12. Further descent of the box will force the buffer rod 20 slightly inward, its inclined face, however, tending to keep the flange in constant yieldable contact with the upper wall 23, such descent bringing the portion of wall 23 lying inward of its point of contact with the edge of flange 12 into contact with the upper surface of the flange, and wall 23 is so curved as at 24 that this

contact will provide a continuous rolling pressure which will force the wrapper 13 against the flange in a very even and effective way.

5 When the parts have reached the point shown in Fig. 4, the outer edge 25 of wall 23 will press wrapper 13 into close engagement with the junction of flange 12 and the side wall of the box, it being noted that the 10 curved portion 24 is so shaped in this position that edge 25 is approximately opposite the axis of the roller. Consequently the motion of the box downwardly, carrying wrapped flange 12 out of the slot 19, will 15 also roll the roller 17 upwardly in continuous contact with the side of the box, pressing the wrapper firmly in position and furnishing no opportunity for the roller face, or wall 23 of the slot, to leave the surface 20 of the box from the time flange 12 first contacts with the wall 23 to the time when roller 17 passes above the upper edge of the box.

While I have described the preferred 25 form of my invention, it will be apparent that certain modifications thereof and different ways of applying the same to accomplish its purpose are possible; and I do not consider my invention to be limited to the 30 exact form herein disclosed; as it is commensurate with the scope thereof disclosed in the specification and indicated in the claims.

I claim:

35 1. In a machine for wrapping extension bottom boxes adapted to pass the box, bottom first, through wrapping mechanism, means operated by the passage of the box to apply the wrapper to the upper face of 40 the extension edge of the box bottom by substantially rolling pressure.

2. In a machine for wrapping extension bottom boxes adapted to pass the box, bottom first, through wrapping mechanism, a 45 rotating element, means for revolving the element, and means carried thereby and actuated by the revolution thereof to apply the wrapper to the upper face of the extension edge of the box bottom by substantially rolling pressure.

50 3. In a machine for wrapping extension bottom boxes adapted to pass the box, bottom first, through wrapping mechanism, a roller, means carried thereby actuated by the passage of the box to revolve the roller,

and means carried by the roller and actuated by the revolution thereof to apply the wrapper to the upper face of the extension edge of the box bottom by substantially rolling pressure.

5 4. In a machine for wrapping extension bottom boxes adapted to pass the box, bottom first, through wrapping mechanism, a roller having a longitudinal slot located in the path of the extension edge of the box bottom and adapted to receive said edge, means for rotating the roller, and means carried by the roller and actuated by the revolution thereof for applying the wrapper to the upper face of the extension edge by 10 substantially rolling pressure.

5. In a machine for wrapping extension bottom boxes adapted to pass the box, bottom first, through wrapping mechanism, a roller having a longitudinal slot adapted to receive the extension edge of the box bottom, and a curved outer portion of the upper wall of the slot adapted to engage the upper face of the extension edge.

6. In a machine for wrapping extension bottom boxes adapted to pass the box, bottom first, through wrapping mechanism, a roller having a slot in the path of the extension edge of the box bottom and adapted to be rotated by the engagement of said edge with the slot, the outer portion of the upper face of the slot being curved outwardly away from the opposite face of the slot to provide a curved pressure surface adapted to apply the wrapper to the upper 90 face of the extension edge by substantially rolling pressure, and means for maintaining the pressure surface in operative contact with the upper face of said edge.

7. In a machine for wrapping extension bottom boxes adapted to pass the box, bottom first, through wrapping mechanism, a roller having a longitudinal slot adapted to receive the extension edge of the box bottom, and a curved outer portion of the upper wall of said slot adapted to engage the upper face of the extension edge, said curve being formed so that a plane through the axis of the roller is tangent to the curve at its point of junction with the periphery 105 of the roller.

Signed at Denver, in the county of Denver and State of Colorado, this 8th day of Sept., A. D. 1919.

ALFRED J. MORRISON.
